Fred C. Harper, Waterville, Maine, assignor, by
mesne assignments, to The Canal National
Bank of Portland, Portland, Maine, a national
banking association, and William B. Nulty,
Portland, Maine, as trustees

Application March 20, 1950, Serial No. 8,649

Term of patent 14 years

(Cl. D58—13)

To all whom it may concern:

Be it known that I, Fred C. Harper, a citizen of the United States, residing at Waterville, in the county of Somerset, State of Maine, have invented a new, original, and ornamental Design for a Pack for Fragile Articles, of which the following is a specification, reference being had to the accompanying drawing, forming part thereof.

Fig. 1 is a top plan view of a pack for fragile articles showing my new design, the pack being open;

Fig. 2 is a front elevation partially in section, of the pack in closed position; and,

Fig. 3 is an end elevation of the pack in closed position.

I claim:

The ornamental design for a pack for fragile articles, substantially as shown.

FRED C. HARPER.
